UNITED STATES PATENT OFFICE.

WOODBURY D. ROBERTS, OF PORTLAND, OREGON.

PADLOCK.

SPECIFICATION forming part of Letters Patent No. 585,594, dated June 29, 1897.

Application filed December 24, 1896. Serial No. 616,878. (No model.)

To all whom it may concern:

Be it known that I, WOODBURY D. ROBERTS, residing at Portland, in the county of Multnomah and State of Oregon, have invented a new and Improved Lock, of which the following is a specification.

My invention is in the nature of an improved hasp or pad lock, and more particularly relates to improvements on my Patent No. 568,701, granted September 29, 1896.

The lock disclosed in my patent referred to consists, essentially, of a pair of pivoted jaws having hooked connections at the free or unpivoted ends, one of such jaws having a bodily endwise movement, so its hooked end can be moved to disengage its fellow member before the jaws can be separated, such lock also having suitable lock mechanism for holding the jaws to their closed position.

In the construction of the lock disclosed by the patent referred to the several parts are so arranged that a double movement of the endwise-movable jaw is required to bring it to a locked position—*i. e.*, it must be first swung to a closed position to engage its fellow member and then endwise to admit the locking devices to operate to hold the jaws to a locked position, such independent movements, owing to the arrangement of the several parts, requiring the manipulation of the lock by both hands.

The primary object of this invention is to provide a lock having a jaw held for endwise movement on its fellow member, which when swung to its closed position will receive its endwise movement by engaging with its fellow member, whereby the lock can be readily closed by one hand, the endwise movement being effected, as it were, by forcing the pivoted jaw against its fellow member.

The present invention also seeks to simplify the construction of the several parts of my former lock and especially to provide a very simple and easily-constructed lock device for holding the jaws locked which cannot be picked.

Furthermore, this invention has for its object to provide a simple and durable spring device for throwing the pivoted jaw open when the lock devices are key-released.

With other objects in view, which will hereinafter appear, the invention consists in the

peculiar construction and novel combination of the several parts, all of which will be first described in detail and then be specifically pointed out in the appended claims, reference being had to the accompanying drawings, in which—

Figure 1 is a plan view of my improved lock, the jaws being in a locked position. Fig. 2 is a similar view of the same, the jaws being open. Fig. 3 is a plan view, the cap-plate being removed and the pivoted jaw, being unlocked, swung in and about to engage its fellow jaw member. Fig. 4 is a detail section taken on the line 4-4 of Fig. 3. Fig. 5 is a similar view, the parts being shown in their unlocked position. Fig. 6 is a plan view, on an enlarged scale, of the pivoted ends of the jaws, the lock, and the spring devices, the cap-plate being indicated in dotted lines. Fig. 7 is a detail view of the pivoted-jaw-opening spring. Fig. 8 is a view of the cap-plate, and Fig. 9 is a view of the tumbler or spring detent hereinafter referred to. Fig. 10 is a view of one form of key used with my lock.

The present form of lock comprises two jaws or members A and B, which have substantially the shape shown, or may be of any other desired shape, so far as relates to the body portion of the jaws. In every instance, however, the ends of the jaws are adapted to interlock. The pivot ends of the jaws are provided with ears or hinge portions C and C', through which passes a pivot or rivet pin D. The opening E in the ear portion C and in the cap-plate F is circular, while the opening E' in the ear C' of the pivoted jaw is elongated, with its major axis at an angle to the line centrally dividing the heads of the jaws A and B, the purpose of such elongation being to permit the hook ends of the jaws A and B to clear each other and to admit of a bodily endwise movement of the pivoted jaw on the fixed jaw, for a purpose presently explained.

In my patented lock hereinbefore referred to the free ends of the jaws terminate in arrow or spear shaped heads, which are adapted to interlock when such pivoted jaw is moved bodily endwise by hand.

In the present form the jaws also have spear or arrow shaped ends A' B', which, however, terminate in cut-off or abrupt portions a' b', cut at an angle or bevel substantially at an

angle parallel with the major axis of the elongated pivot-opening in the ear C', the undercut or lock portion a^2 and b^2 of such heads being also beveled or angled, as shown. The object in thus constructing the lock ends of the jaw is twofold. First, it provides a means whereby the pivoted jaw B is caused to move bodily endwise on its pivot as it is closed up against its fellow A. This operation will be clearly understood by referring to Fig. 3. Thus when the jaw B is swung to a closed position, which is readily effected by one hand, until its bevel end $a' b'$ and $a^2 b^2$ contact, and further pressure applied on the jaw B in the direction indicated by the arrow 10, the incline or beveled ends of the jaws will cause the jaw B as it is thus further closed in to move bodily endwise in the direction indicated by the arrow 20, it being obvious that as the inclined faces or angles of the lock portions are in a plane parallel with the elongated pivotal opening such jaw will readily move up in a position to be held locked by the locking devices presently referred to, such construction of parts providing, as it were, practically an automatic means for imparting the bodily endwise movement to the pivoted jaw. Secondly, as the lock-necks or undercut portions are disposed at an angle to the direct central or pull line of the lock the lock strength of the jaws is thereby materially increased, as the same cannot be readily pulled apart by any unusual strain thereon.

To lock the jaws when they are closed together, I provide the head a^3 of the member A with a recess or socket G, in which is held a slide-bolt H, forced normally outward by a spring h, so its front end will engage a shoulder I on the ear C', as clearly shown in Fig. 6. The bolt H has a cut-out or socket portion h' , in which is held a tumbler or detent J, the upper face of which is beveled in the direction of the key-slot K, which face is normally held in a plane above the top of the bolt H by means of the spring k.

L indicates the cap-plate, which is riveted onto the body of the jaw A and which has guideways l and l' on its under face of irregular lengths, which with the key-slots K K' form the ways for the wards of the key M.

While I have shown the lock formed with ways for a key having but two wards $m m'$, it is obvious that a greater number of ways may be provided to receive keys having an increased number of wards. In all instances, however, one of the wards of the key is made long enough to pass through the lock-head of the jaws A and beveled, as shown at m^2 , to engage the beveled detent J. The cap-plate L has a pendent ward l^2 , which when the parts are in their locked position, as shown in Fig. 5, projects down at the rear end of the detent J and forms a lock-stop to prevent the bolt being moved endwise.

While the ward l^2 forms a lock-stop, it also forms an effectual means to prevent picking the lock by a wire or other device. Thus

should a wire be inserted through the keyway at the rear of the ward l^2 to engage the incline or key-engaging portion h^2 of the bolt such ward l^2 will prevent the bolt from moving endwise, it also forming an abutment to prevent a wire or other implement from being moved against the portion h^2 , which might be entered in the keyway to depress the detent J. 75

So far as described it will be readily seen that when the proper key is inserted its ward m will first depress the detent J, after which its ward m' will engage the portion h^2 of the bolt and force it endwise out of a locked engagement with the ear C', the detent J during such interlocked position of the bolt being held down in its recesses by the ward l^2 , as clearly shown in Fig. 4, it rising up again in front of such ward l^2 as soon as the bolt H 85 moves back to its locking position.

In the present invention I have also provided simplified and more effective spring devices for throwing open the jaw B when unlocked. By referring more particularly to Figs. 6 and 7 it will be seen that the ear C' is provided with a recess c^2 , in the outer end of which is a socket c^3 to receive the spiral end n of a bow-spring wire N, which bows about the pivot of the jaws and terminates in an eye 95 or hook end n' to receive a pendent lug l^5 on the cap-plate, such lug being so arranged that when the cap-plate is placed in position a tension will be imparted to the said spring which will serve to throw the jaw B open when released, the spring N having its end n^2 fixedly connected to the ear C', as shown.

By providing a spring device arranged as shown it is obvious that when the jaw is unlocked the spring as it expands will as it 105 throws such jaw open also force it bodily endwise outward at the same time.

Having thus described my invention, what I claim, and desire to secure by Letters Patent, is—

1. In a padlock, a jaw pivoted at one of its ends to its fellow member, and at its opposite end hooked to its fellow member, said jaw having bodily endwise movement to disengage its hook before swinging open on its pivot, such jaws having their hook ends provided with engaging members inclined at a plane at an angle to a line drawn vertically through the pivot and the hinged ends, whereby a lateral compression of the jaws will 115 cause the swinging jaw to move endwise on its pivot as its hook end locks with its mate as specified.

2. In a lock as described, the combination of the jaws pivotally joined at one end and having interlocking means at the other end, one of said jaws having an endwise movement on its mate, a cap-plate secured to such mate having a pendent lug, a bow-spring secured at one end to the endwise-movable jaw 130 and having its other end held in a hooked engagement with the cap-lug, and means for holding the jaws to a locked engagement substantially as shown and described.

3. In a lock of the kind described, the combination with the jaws, pivotally connected in the manner set forth, one of said jaws having a recess therein, the other a lock-shoulder, a slide-bolt held in such recess, a spring-elevated detent, adapted to project above the slide-bolt, a cap-plate having a pendent ward projected at the rear of the aforesaid detent, said cap-plate and recessed jaw having key-ways substantially as shown and described.

4. In a lock of the kind described, the combination with the jaws pivotally connected in the manner set forth one of such jaws having

a recess and key guides or openings a slide-bolt held in such recess, having a detent or 15 lock member adapted to be moved out of an operative position on the insertion of a proper key, and a cap-plate having a ward to form a stop to engage the said detent and prevent the slide-bolt moving endwise, all arranged 20 substantially as shown and described.
